SHOEMAKING

Verne L. Kneeland, Manchester, N. H.

Application March 9, 1948, Serial No. 13,829

7 Claims. (Cl. 12—145)

1

This invention consists in a new and improved process of making shoes more accurately and more economically than heretofore. While it may be applied with particular advantage to the manufacture of two-piece slippers, it is not in any sense limited to that or any specific type of shoe, but is of more general application.

The process of this invention is characterized by the steps of gauging the counter portion of the upper by gauge clamps on the last or form itself which hold the counter with its top line accurately located and its marginal edge projecting above the last bottom and then, while these parts are so held, presenting the heel end of an insole within the projecting outline of the counter and wiping in and tacking the heel seat. In this operation the wings of the counter are wiped in to such an extent as to eliminate the necessity of further lasting. They require merely to be fastened in position, by tacks or staples driven at their forward corners.

The process of this invention not only eliminates the assembling operation, but provides a better fitted and more accurate heel seat than it has been possible to secure when the more or less uncertain assembling operation is relied upon. The inner surface of the counter is brought up more uniformly and continuously to the contour of the last and to the margin of the insole and fastened more securely in that position than when the rear portion of the upper is located by one or two tacks driven in the usual assembling operation and the draft of a pulling-over machine is relied upon to bring about the desired contour of the upper. Incidentally, an advantage of eliminating the assembling operation is that the necessity for driving tacks through the counter portion of the upper is entirely avoided.

Another advantage of the process of the invention is that the insole is located upon the last bottom more accurately than heretofore, and that the insole tacking operation is reduced to one or two tacks in the forepart of the insole. It will be understood that the heel seat and adjacent portions of the insole are accurately gauged on the last bottom by the upstanding walls of the counter, which include the usual counter stiffener, and that all that is required in addition to this is a single tack at the toe of the insole. The process of the invention accordingly results in a substantial saving of tacks as well as a reduction in the time and extent of the insole tacking operation.

Another advantage of the process of this invention is that the draft on the forepart of the upper in the pulling-over operation is substantially improved over that to which the upper is subjected when its partially formed counter portion has been merely secured to the last by tacks used in the assembling operation. This is because the rear end of the shoe is completely formed before the pulling-over operation takes place.

10 While the precise nature of the gauging clamps is of secondary importance, I prefer to provide for this purpose sheet metal wings which may be attached to the sides of the cone of the last in combination with gauging edges or points which contact with the top line of the counter and locate it accurately in the proper position on the last.

15 Preferably and as herein shown, the forepart of the upper is attached to the insole in the shank thereof before the insole is presented upon the last bottom. Accordingly, the heel seat nailing step of my improved process accurately and permanently establishes the counter, insole and forepart or vamp of the shoe permanently in the final relation they will occupy in the finished shoe. The shoe is thus brought to the stage at which it may be readily finished by the conventional steps of side-lasting, toe-lasting and sole-attaching.

20 25 30 These and other features of the invention will be best understood and appreciated from the following description of a preferred manner of carrying it out illustrated in the accompanying drawings, in which:

35 Fig. 1 is a view in elevation of a last or a form showing a counter in gauged position thereon.

Fig. 2 is a view in perspective of an assembled insole and vamp.

Fig. 3 is a plan view showing the parts of the 40 shoe as they appear after the heel seat lasting operation.

Fig. 4 is a corresponding view in side elevation.

Fig. 5 is a view in vertical section illustrating the wiping and tacking mechanism of a heel seat 45 lasting machine, and

Fig. 6 is a plan view of the same.

The process of this invention may be carried out by the employment of a counter which is lined or unlined, but it is essential that it includes a stiffening medium of some kind. The counter herein shown comprises an outer integument 10 usually of leather, a counter stiffener 11 usually of moldable fibre, and a lining 12 which is stitched to the finished edge of the counter through the medium of a rolled edge. The coun-

ter as a whole is preferably given a preliminary molding operation, usually referred to as "clam-shelling," although my process has the advantage that this preliminary molding may be omitted in some cases because the clamping gauges which are employed with the last or form are adequate to hold the counter in the required curved condition.

Another important advantage of the novel process of this invention is that it requires a minimum of special equipment. This will be apparent from a consideration of Fig. 1 in which is shown the heel portion 13 of a last having the usual thimble 14 and equipped with a gauge plate 15 and a resilient clamping plate 16. A gauge plate 15 is secured to the cone of the last on each side thereof in position to gauge the counter accurately by engaging its forward curved finished edge, thus determining with extreme accuracy both the proper location of the finished edge of the counter in the completed shoe and the proper distance by which the unfinished margin of the counter should extend beyond or above the heel seat portion 13 of the last. Preferably and as herein shown, each clamping plate 16 and its associated gauge plate 15 are secured to the last by screws 17, but it will be understood these elements may be separately attached if preferred. In carrying out the first step of the process the counter is merely wrapped around the heel end of the last and secured thereon in curved and gauged position by the resilient clamping plates 16.

In Fig. 2 is shown an insole and vamp properly prepared for use in carrying out the process of the invention. The insole 18 may be of any usual construction and may be of full length, or preferably it may terminate as shown in Fig. 2 at about the forward end of the shank. The upper 19 may be assembled with the insole in gauged relation and secured in position by staples 20 driven into the insole at substantially its narrowest part through the rear corners of the vamp.

The next step of the process consists in presenting the rear end of the insole to the last bottom, moving it rearwardly between the upstanding walls of the counter which serve accurately to guide the insole into exactly the proper position on the last bottom and to secure it against displacement during the ensuing steps of the process. The fact that the whole rear end of the insole is thus positively located obviates the necessity of the usual insole tacks. It is usually necessary in carrying out the process of my invention to supplement the hold of the counter on the insole only by a single tack driven near the forward end of the insole.

Having thus located the counter, insole and vamp upon the last in the desired relation, the next step of the process comprises a heel seat lasting operation, and this may be carried out satisfactorily in any heel seat lasting machine available to the industry, for example, that shown in U. S. Patent No. 2,059,241, November 3, 1936, J. C. Jorgensen.

The heel seat lasting operation is illustrated in Figs. 5 and 6 in which are shown the essential operating elements of the machine of this patent. They include a jack post 30 carrying a block 31 adjustable upon a curved support and carrying a spindle 32 which fits into the thimble of the last 13. Disposed vertically above the jack when the latter is in operative position is a holdown member 33 which engages the insole 18 upon the

last bottom and accurately determines the height of the last and the counter clamped thereto with respect to the wipers.

The machine includes in its organization a heel band 34 for embracing and clamping the upper about the heel end of the last, wipers 36 for wiping the marginal portion of the counter inwardly over the insole, and means for driving tacks through openings in the wipers to fasten the upper. The jack 30 is moved by power means not shown to carry the last rearwardly into position to be embraced by the heel band, and then upwardly to force the insole firmly against the holdown 33. The heel band may be formed, for example, of leather molded in approximate conformity to the contour of the heel end of the last, but sufficiently flexible to conform to small variations in the contours of shoes of different sizes and styles. About the contour of the heel band are provided a series of movable blocks 35, one of which is shown in Fig. 5, and these are operated at the proper time in the cycle of the machine to compress the heel band forcibly and conform the counter accurately to the contour of the last 13.

Each of the two wipers 36 is secured to a tack block 45 from which tacks are driven through openings in the wipers to fasten the upper in lasted position. One of these openings is shown at 46 in Fig. 5. Each wiper has thereon an upstanding flange 47 which cooperates with a plurality of spring pressed tack fingers 48 mounted in recesses in the tack block 45 to provide pockets for receiving the tacks. Each tack block has tongue and groove connections 49 and 50 with one of the wiper carriers 37 which supports it. These tongue and groove connections are curved so that the tack block and the wiper attached thereto may be conveniently disconnected from the wiper carrier by sliding the tack block forward. Each tack block is secured to the wiper carrier 37 by means of a screw 51 which may be conveniently removed from above when the wipers are in their closed position as illustrated in Fig. 6.

The two wiper carriers 37 are supported on a slide 38 movable forwardly and rearwardly along guideways in the machine frame, and each carrier is guided for movement about a central vertical axis indicated at X in Fig. 6 by means of a tongue 39 which projects downwardly from the carriers into a circular groove 40 in the slide 38. The wiper carriers are confined on the slide 38 by a cover plate 43. The slide 38 is moved forward to impart to the wipers their advancing movements lengthwise of the last by mechanism not herein shown. Closing movement is imparted to the wipers through links 42 which are connected to the respective wipers by pins 41 as shown in Fig. 6.

The tacks for fastening the heel end of the upper in lasted position are driven by a plurality of tack drivers 52 operating in passages in the tack block and arranged in an outline corresponding to that of the heel seat of the shoe. The drivers 52 are secured at their upper ends in curved driver blocks 53 movable in a curved recess provided in the tack block. Accordingly, each driver block 53 is movable with the wipers as the latter are advanced and closed in over the shoe bottom. Tacks are supplied to the driver passages through flexible tubes 54.

In operation the last 13, with the counter clamped and gauged in position thereon, is placed upon the spindle 32. The jack is moved forcibly

rearwardly, bringing the counter into engagement with the heel band 34. The heel band 34 is then contracted by power, conforming the counter to the last without in any way disturbing its gauged position and causing its walls to project above the last bottom, the clamping plates 16 and the flexible band yielding and conforming to each other where the clamping plates are overlapped. The insole is presented within the walls of the counter and upon the last bottom and elevated by movement of the jack into engagement with the holddown 33. The wipers 36 are then advanced and closed. This operation may be repeated more than once if desired and the jack again slightly elevated between the strokes of the wiper. When the wiping operation has been satisfactorily completed, the drivers 52 descend and tacks are driven through the overwiped margin of the counter and clenched against the iron bottom of the last.

In this operation the forward corners of the counter are brought in above the rear ends of the vamp 19 and may be tacked in that position by tacks 21. This in effect completes the rear end of the shoe and it may now be passed directly to the pulling over machine and completed by the conventional operations usually followed from that point in shoemaking.

Having thus disclosed my invention and described one illustrative manner of carrying it out, I claim as new and desire to secure by Letters Patent:

1. The shoemaking process which comprises the steps of curving the counter portion of an upper about the rear end of a last, gauging the upper as to height, presenting the rear end of an insole to the last bottom between the upstanding walls of the said counter portion, and then heel seat lasting and tacking the said counter portion.

2. The shoemaking process which comprises the steps of securing the stiffened counter portion of an upper to the side walls of an inverted last, gauging the finished edge of the upper on the cone of the last to present the marginal edge of the upper projecting as a stiff wall upstanding about the heel seat of the last, locating the rear end of an insole on the last bottom within the wall furnished by the counter portion of the upper, and then heel seat lasting the said counter portion and tacking it to the insole.

3. The shoemaking process which comprises the steps of clamping an unmolded counter to the rear end of a last-shaped form with its margin projecting a gauged distance beyond the bottom of the form, engaging the counter with a flexible heel band and forcibly conforming it to the contour of the form, inserting an insole

between the sides of the conformed counter, and then heel-seat lasting the counter.

4. The shoemaking process which comprises the steps of clamping a counter to the rear end of a last with its margin projecting a gauged distance beyond the last bottom, conforming the counter to the contour of the last, gauging to the upstanding walls of the counter an insole having a vamp fastened at its rear corners to the shank of the insole, heel-seat lasting the counter and bringing its forward corners inwardly above the vamp, and then tacking the corners of the counter to the insole.

5. A shoemaking process which includes the steps of securing a lined counter to the rear end of a last by gauging and clamping devices which project from the opposite sides of the cone of the last, then conforming the counter to the contour of the last by a flexible band that yields to enclose the gauging and clamping devices, and finally heel-seat lasting the counter while thus held in conformed condition.

6. The shoemaking process which comprises the steps of nailing the flange of a molded counter to the heel-seat end of an insole while leaving free the forward corners of the counter, bringing the rear corners of a vamp into lapping relation with the corners of the counter, and then inserting metallic fasteners through the lapping corners of the counter and vamp and also through the insole beneath them.

7. A shoemaking process including the step of uniting the heel seat and shank portion of an insole to the flange of a molded counter portion while leaving free the forward ends of the counter portion, locating the rear corners of a vamp in gauged position beneath the ends of the counter portion, and then driving metallic fasteners through the ends of the counter portion, the vamp and the underlying portion of the insole substantially at the narrowest part of the shank.

VERNE L. KNEELAND.
